UNITED STATES PATENT OFFICE.

WILLIAM H. HUDSON, OF MONTGOMERY, ALABAMA.

SURGICAL FORCEPS.

988,939.

Specification of Letters Patent.

Patented Apr. 4, 1911.

Application filed November 30, 1909. Serial No. 530,650.

To all whom it may concern:

Be it known that I, WILLIAM H. HUDSON, a citizen of the United States, residing at Montgomery, in the county of Montgomery and State of Alabama, have invented certain new and useful Improvements in Surgical Forceps, of which the following is a specification.

My invention relates to improvements in surgical forceps, and relates particularly to instruments of this type for use in head surgery.

In performing the trephining operation, and more particularly in forming the osteoplastic flap or trap-door, the best practice is to first form a plurality of openings in the skull, and then connect the openings by means of narrow channels or canals, these channels and openings forming the outlines of the flap. The openings are formed by a suitable trephining instrument or instruments, and extend through the skull but do not penetrate the membrane (the dura mater) forming the covering of the brain, and inasmuch as it is essential that this covering be not penetrated or affected in any material degree, the instrument for forming the connecting channels must be so arranged as to operate from the inner side of the skull and move outwardly, being so formed as to provide a minimum liability of affecting the membrane during the operation.

The present invention relates more particularly to the instrument for forming the connecting channels.

Instruments for this purpose heretofore provided and which are formed with three members have been arranged in such form as to provide a movement of the inner cutter in a straight vertical line, the opposing cutter being carried by one member acts also in a vertical line. The movements of the two opposing cutters are in parallel lines, therefore providing an operative movement, similar to that of a punch.

In use, instruments having the straight line movements have been found unsatisfactory excepting possibly in the thinnest portions of the skull, where the pressure required in causing the inner cutter to pass through the skull may be provided by the operator using simply the ordinary handles; where the thicker portions of the skull are encountered, the pressure required in closing the handles is so great as to make it im-

possible to be applied by a hand grip, and where the skull is of maximum thickness is restricted to practically a shaving, the cutter acting more in the manner of a scraper than as a cutter. This results in the requirement of the expenditure of a large amount of time in making the channel, the channel cutting, under the most favorable circumstances, requiring from ten to eighteen separate operations to the inch, this number increasing as the thickness of the skull increases.

The present invention, while having the same general object in view as prior instruments referred to, viz., the forming of the connecting channels, provides this result with a greatly increased rapidity, and at the same time, provides all possible restrictions against affecting the brain membrane heretofore referred to, each cutting operation removing a "bite" of skull material of considerable size, thereby requiring a less number of cutting operations than with any of the instruments heretofore produced for this purpose. In actual practice, I have found that where the instruments heretofore provided have removed but small bites or shavings of the material, the instrument forming the subject matter of this invention uniformly removed "bites" of a length ranging from one-fifth to one-sixteenth of an inch with each operation, depending upon the thickness of the skull, the relative number of operations required to produce the same length of channel being from four to ten to one in favor of the instrument herein set forth. To produce this result the principle of operation of the forceps is modified from that of having the inner cutter moving in a straight line to that of having the path of movement of this inner cutter extending in a curved line of greater radius than the radius of the line corresponding with the path of movement of the outer cutter, thereby providing two cutters having relatively curved paths of movement, these paths extending on lines having different radii and intersecting one another. By this particular form of relative movement, the inner cutter tends constantly to move forward in the direction of cutting and thereby provides a substantially curved wall when the bite has been removed, the blades having a reverse shear action.

Another object is to provide an instrument of this type with means for adjust-

ably controlling the length of the distance between the cutters in open position, thereby preventing liability of penetrating the skull to a greater depth than is absolutely required to permit of forming the bite.

5 A further object is to provide a cutting blade of maximum strength and capable of resharpening when desired, but formed in such manner as to be readily reinserted into 10 the channel after the bite has been removed.

15 A further object is to provide means for deadening the shock produced by contact of the handles as the bite is completed.

20 To these and other ends, the nature of which will be readily understood as the invention is hereinafter disclosed, said invention consists in the improved construction and combination of parts hereinafter fully described, illustrated in the accompanying 25 drawings, and particularly pointed out in the appended claims.

25 In the accompanying drawings, in which similar reference characters indicate similar parts in each of the views, Figure 1 is a side elevation of an instrument embodying my invention, parts being shown in section, the cutters being shown in open position, said view also showing the arcs indicating the 30 lines of relative paths of movements of the respective cutters. Fig. 2 is a similar view showing the cutters in closed position. Fig. 3 is a top plan view of the forward end of the instrument. Fig. 4 is a sectional view taken through the shank of the movable cutter. Fig. 5 is a sectional view taken on the line 5—5 of Fig. 4.

35 The instrument herein shown is a forceps of the type having three members, and embodies two pivotally connected members, 40 one of which is formed with one of the cutting members, the other pivotal member carrying the complementary cutter, the connection between the latter cutter and its carrying member being a pivotal one.

45 10 and 11 designate the two members pivotally connected together by means of a suitable connection 12 forming a fixed pivot point for the two members. Each of said members has its rearwardly extending portion in the form of a handle of any preferred type, the rear portion being preferably roughened, as at 13, each handle having outwardly extending portions 14 that serve as engaging members for the hand of the operator in manipulating the instrument in a forward direction. The handles are normally retained separated by means of a spring 15, while one of the handles is provided with a plate 16, of suitable metal, and 50 which serves to deaden the shock produced by the closing of the handles in use, any suitable material which will produce this result, being employed, as for instance, copper. This plate is shown as secured to the handle 55 10 by suitable screws 17; it will be readily

understood however, that it may be carried by the handle 11 instead, or each handle may be provided with a plate for this purpose.

60 The forward end of the member 10 is 70 formed substantially as shown in Fig. 1, being inclined downwardly to a more or less degree, and having an opening 18 extending therethrough, in a substantially vertical direction, said opening having continuous 75 walls formed by the side portions 19, the front portion 20 and rear portion 21. The front portion 20 is of less height than the general height of the forward end of this member, the upper portion being cut away 80 as indicated; the lower face of the portion 20, however, extends in a plane corresponding with the lower plane of the forward end of the member, said lower face being in the form of a cutting edge 22, said edge following a contour similar to that of the movable cutter, presently described, but being of a size sufficiently larger than the side of the movable cutter to provide a space between the cutters when the latter are in 85 closed position. The portion 20 is curved in horizontal section to permit of the use of a movable cutting blade having its forward end rounded as indicated in Fig. 4. The length of the cutting face 22, is sufficient to 90 provide a coöperating face with the entire cutting portion of the movable cutter.

95 As it is desirable in some cases, that the bite be provided by a severance not wholly due to the passage of the movable cutter through the skull, I form the portion 20 with a rounded face 23 leading to the cutting edge 22, this construction permitting a lifting movement of the instrument with the cutting edge 22 as a fulcrum, and thereby 100 permit the bite to be made not simply by a closing of the handles, but also by a relative pivotal movement of the instrument, with the cutting edge as the pivot point, the 105 particular shape indicated, permitting such pivotal or rocking movement without a tendency of the instrument to slip during the movement.

110 The rear wall 21 of the opening is curved in the direction of its vertical length, as shown in Fig. 1, and forms a riding face for the shank of the movable cutter 24, said cutter being pivotally mounted as at 25 within the forward end of the member 11, said cutter also having its rear face curved 115 in the direction of its length to permit it to have an extended contact with the wall 21 during the movement of the cutter. To retain the cutter 24 in contact with said wall 21, I provide a pin 26 which extends from one side wall to the other at a sufficient distance from the front of the wall 21 to provide a passageway for the shank 27 of the cutter 24.

120 125 130 The movable cutter 24 is formed of the

shank portion 27 and cutting portion 28, the latter being in the form of a hook continuation of the shank, the inner face of the hook providing the cutting edges, the portion 28 being preferably of the cross-sectional configuration indicated in Fig. 5, the lateral width of said portion being slightly in excess of the width of the shank portion 27, as indicated in Fig. 4.

10 To control the length of movement of the movable cutter, I provide one of the members, preferably the member 11, with an adjusting screw 29, one end of which is adapted to contact with the opposite member 15 when the handles are in their open position, said screws serving to adjustably limit the opening movement of the members, this adjustment being used for the purpose of accommodating the instrument to different 20 thicknesses of skull, it being understood that the opposite extreme of relative movement of the cutters is the same regardless of the length of movements of the cutters.

As shown in Fig. 1 (wherein the line x 25 represents the arc that would be traversed during a pivotal movement of the cutting edge 22, and y the arc traversed by the movable cutter), the arcs corresponding with the respective paths of movement of the cutters have different radii, that of the movable cutter being greater than that for the relatively stationary cutter 22, the two arcs intersecting each other. Obviously the movement of the movable cutter will be such 30 as tend to carry the front end of the cutter forwardly as it continues its course through the skull with the result that the bite so formed will have an approximately straight 35 wall through the skull, this tendency to 40 "eat" forwardly into the bone as the handles are closed, eliminating the gradually rounding effect produced by the instrument heretofore used for this purpose.

The particular cross-sectional forms of the 45 movable cutter shown in Figs. 4 and 5, are of special value in operation. In use, the completion of a bite carries the movable cutter out of the channel and therefore to reinsert it the movable cutter is passed through 50 the trephined opening and moved along the

channel portion previously cut, the lesser width of the shank permitting of a free movement of the cutter through the channel to proper position. The particular curvature of the outer face of the cutting portion 28 both laterally and in the direction of length of the cutter, provides a special advantage in the use of the instrument due to the fact that there is practically no liability 55 of the membrane, which lies beneath the skull, being damaged during the forward movement of the movable cutter to a position which will provide for a new bite, the rounded forward portion serving to gradually press this membrane away from the 60 skull and permit the cutting edge to pass into operative position.

Having thus described my invention what I claim as new is:—

1. In an instrument of the class described, two pivotally connected members, one of said members having an opening formed with a rear wall curved in the direction of its length, the opposing wall terminating in a cutting face, and a movable cutter carried 70 by the other member and adapted to coact with said cutting face during pivotal movements of said members, said cutter having a sliding contact with said rear wall during the cutting movements, and means carried 75 by the cutting member adapted to retain the cutter in contact with said curved wall, whereby the movement of the cutter will be limited to movements extending in a line 80 corresponding with the arc of a circle. 85

2. In an instrument of the class described, two pivotally connected members each carrying cutting faces, means to limit the opening movement of the members to control the space between the cutting faces for the reception of the material to be cut, and a shock-deadening plate carried by one of said members and adapted to limit the closing 90 movement of the members.

In testimony whereof I affix my signature 95 in presence of two witnesses.

WILLIAM H. HUDSON.
